UNITED STATES PATENT OFFICE

CHESTER F. JOHNSON, OF DETROIT, MICHIGAN.

CARBURETER.

1,093,627.

Specification of Letters Patent. Patented Apr. 21, 1914.

Application filed April 10, 1912. Serial No. 689,706.

To all whom it may concern:

Be it known that I, CHESTER F. JOHNSON, a citizen of the United States, and a resident of Detroit, in the county of Wayne and State of Michigan, have invented a new and Improved Carbureter, of which the following is a specification.

This invention relates to means for producing an explosive fluid for use in internal combustion engines; and its object is to provide means to produce such fuel at all times irrespective of the temperature of the surrounding atmosphere.

This invention consists in combination 15 with a float chamber and a nozzle leading therefrom for the discharge of the liquid fuel, of a carbureting chamber so constructed that the current of inrushing air will be 20 strangled so as to cause increased speed and thorough mixing, of an electric heater for raising the temperature of this carbureting chamber, and a cylindrical chamber connected to said carbureting chamber, the temperature of which may be kept above that 25 of the surrounding atmosphere by means of a water jacket through which the circulating water from the engine may pass on its way to the radiator.

In the accompanying drawings Figure 1 30 is a vertical, central section of this improved carbureter. Fig. 2 is a plan of the electric heater and the carbureting chamber. Fig. 3 is an elevation of the lower portion of the carbureter looking from the left in Fig. 1. 35 Similar reference characters refer to like parts throughout the several views.

This carbureter comprises a body 1, a float chamber 2 and a tube 3 which connects to the body 1. The body and float chamber are 40 secured together by means of the screws 4, and the fuel passes to the carbureter through a connection 5. The float 6 is annular and secured to a lever 7 mounted on a pivot 8. A ball 9 on the valve-stem 10 is secured in 45 proper relation to the lever 7 by means of a nut 11. The valve 12 on the rod 10, controls the flow of fuel into the float chamber. The top of the float chamber is formed by a cap 14, which carries the nozzle 15. A stem 16 50 is threaded in this nozzle 15 and has a needle-valve 17 which controls the flow of the fuel through the discharge aperture 18 of the nozzle. The fuel flows up through a groove 19 in the stem 16. A stuffing-box 20 55 prevents leakage around the lower end of the stem 16. As the stem 16 is threaded in

the nozzle 15 and slidable in the stuffing-box, any expansion of the float-chamber does not affect the adjustment of the needle-valve at the upper end of the stem.

A plug 22 may be employed to drain the float chamber. In order to prevent the stem 16 from turning after once being adjusted, a knob 23 may be secured to its lower end, which is engaged by a spring-pressed pin 24 60 slidably mounted in the lower end of the bracket 25, the spring 26 on the stem 24 holding the point of the pin against the knob 23, which is preferably roughened or knurled.

The line 27 in Fig. 1 indicates the normal fuel level which is just below the upper end of the nozzle 15. In case it is necessary or desirable to raise the height of the fuel in the carbureting chamber, as will be explained later on, the float 6 may be depressed by means of the stem 28, mounted in the bracket 29. A spring 30 normally holds this stem outward, but it can be depressed by means of the small bell-crank lever 31, 70 in which case more fuel will flow into the float-chamber and the level therein and in the carbureting-chamber will be raised.

The carbureting-chamber is composed of a strangle tube 34 tapering downward and 75 having its lower end below the level of the fuel. This strangle tube connects to a diaphragm 35 having a downwardly turned flange 36, the lower edge of which engages the cap 14. This downturned edge 36 is 80 provided with a number of apertures 37, and the air enters through the annular space 38 between the flange 39 on the body 1, and the upper edge of the float chamber 2 and passes through these holes 37 into the 85 space between the cap 14 and the diaphragm 35, and then down and up through the strangle tube 34. During the time the engine is running, the fuel leaving the discharge opening 18 of the nozzle 15, will be 90 carbureted immediately, and while the engine is standing still, the flow of fuel from the aperture 18 will cease because said aperture is above the fuel level. When the engine is to be started, a richer mixture is 95 usually desired, and therefore the float 6 is depressed so that the fuel level will rise in the float chamber sufficiently to cause the fuel to flow from the aperture 18 into the cup formed by the depression of the cap 14. 100 When the engine is now turned-over by hand, the air drawn in through the holes 37

will pass through the fuel lying in the depression in the cap 14, and carry up a much larger percentage, so that the mixture will be very rich.

5 During cold weather, the fuel does not readily carburet, so that it is desirable to raise its temperature, which may be done by the following device. In the groove between the strangle tube 34 and the diaphragm 35, 10 a heating element such as the coil 42 of wire of proper resistance to electric currents is placed and insulated from both the diaphragm and the tube by means of thin sheets of proper material 43, such as asbestos. The 15 ends of the coil connect to curved plates 44, such as shown in Fig. 2, which are properly mounted on the strangle tube 34, and which are so constructed as to contact with the screws 45 of the binding posts 46. Proper 20 circuit wires, leading to a storage battery or other source of supply, connect to these binding posts and permit the passage of a current which will heat the wire 42 and thereby the tube 34, whose lower end extends down into the fuel in the depression in the cap 14. This will cause the liquid fuel to be heated, and will also tend to volatilize the same, so that the vapor therefrom 25 will immediately mix with the incoming 30 air from the holes 37.

It is desirable that the explosive mixture be kept at the highest temperature consistent with safety as it passes to the engine. This may be done by forming the body 1 35 with a tubular extension 3, which serves as a water jacket for the inner tube 49. A portion of the circulating water from the engine may enter the spaces between the tube 49 and the shell 3 through the passage 50, 40 and leave through the passage 51 shown in Fig. 3. It is readily seen that the construction shown in Fig. 1 is very feasible from a manufacturing standpoint, as the extension 3 may be cored at the same time as the 45 other portions of the body 1, and that it can be bored to receive the tube 49, whose ends may be rolled down to form water-tight joints. This construction is preferable to attempting to form the shell 3 and the 50 tube 49 of one casting and separating the two by means of air spaces formed by cores.

A rod 52 extends through the extension 3 and carries the throttle-valve 53. A crank 54 on the outer end of this shaft, may be of 55 any desired construction and furnished with any proper connections, so that it may be controlled from a distance.

It is usually desirable that the explosive mixture coming from the strangle tube 34 60 be mixed with fresh air so as to form a properly proportioned mixture. The body 1 is therefore formed with an extension 55 having a cap 56 into which is screwed a bushing 57, and to which is secured a bracket 65 58. A stem 59 is vertically slidable in this

bushing 57, and on it is slidably mounted a valve 60. On the lower end of this stem 59 is secured a collar 61 between which and the valve is a spring 62. A second collar 63 is rigidly mounted on the stem 59, but bears against the shoulder 64. Between this collar and the valve 60, is a spring 65. The initial tension of the spring 65 is controlled by the position of the bushing 57, although additional tension may be given to this spring by means of the arm 67 secured to the small shaft 68, which is mounted in the bracket 58. An arm 69 secured to this shaft 68 may be operated through any desired type of connector from the control station. By swinging this arm 69 to the left, the stem 59 will be depressed and will carry down the collar 63 and thus compress the spring 65, thereby restraining the air-valve 60 and checking the flow of air to cause the explosive mixture to be richer. By properly proportioning the springs 62 and 65, the valve 60 will be positioned against its seat with substantially no pressure. A collar 71 on the stem, held in position by the pin 74, and spring 72 return the stem 59 after being depressed by this arm 67, while a small spring 73, whose upper end is secured to the collar 63 in any desired manner, preferably by soldering, will cushion the valve 60 at the upper end of its movement, when, by reason of high velocity of the valve, it moves upwardly to the limit of its movement.

The operation of the carburetor is as follows: When it is desired to start the engine, the stem 28 is depressed, causing the valve 12 to lift from its seat, and permitting additional fuel to flow into the float chamber, so that the fuel level will be above the upper end of the nozzle 15, and a small quantity of fuel will accumulate in the depression in the cap 14. If the weather is cold, an electric current is caused to flow through the wire 42, heating the same, and with it the strangle tube 34, which dips into the fuel around the upper end of the nozzle 15. When the fuel is thus heated, it more readily volatilizes, and when the engine is turned-over, the inrushing air passing up 11 through the annular space between the flange 39 on the body and the upper edge of the float-chamber, and through the openings 37 and down underneath the lower edge of the tube 34, and then upward, will carry with 12 it a comparatively large amount of vaporized fuel, thus causing the cylinder to be charged with a very rich mixture which will readily explode. It has been found by experience that explosion engines can be easily 12 started during the coldest weather when a heating device is thus mounted in the carbureting-chamber, and especially surrounding the strangle tube 34. It sometimes happens that fuel particles of considerable size 130

- are carried up from the strangle tube by the inrushing air and then fall onto the diaphragm 35 and into the tube 34. Any fuel which falls into the tube 34 will immediately flow down into the depression in the cap 14. This tube 34 is provided with small perforations 77 through which any liquid fuel resting on the diaphragm 35 may drain into the tube 34 and then down into the depression in the cap 14. As the diaphragm 35 is heated at the same time as the tube 34, much of the fuel which falls back on it is vaporized by the heat, thus adding to the effectiveness of the carburetor. As stated before, the air-valve 60 permits flow of air through the carburetor, which mixes with the vapor which passes upwardly from the strangle tube 34. The amount of fuel which flows out of the apertures 18 will depend upon the difference in air pressure between that in the pipe 40 and in the float chamber 2, which is usually atmospheric. The distance the valve 60 opens will depend upon the same difference, so that normally, the amount of fuel will be in a predetermined proportion to the air. If then it is desired to increase the proportion of fuel, the arm 69 is swung to the left, increasing the tension of the spring 65 and checking the amount of air which passes into the body 1 of the carburetor. It has been found that by the use of the water jacket between the walls 49 and 3, liquid fuel of a much lower degree of volatilization may be used, and that by the use of the heating coil 42, explosion engines may be started with liquid fuel which is normally stable, such as kerosene. By removing the screws 4, the float-chamber and the head 35, coil 42 and tube 34 can be separated from the body of the carburetor.
- I claim.
1. In a carburetor, the combination of a body, a float-chamber secured thereto, a cap forming a top for the float-chamber and having a central depression, a fuel nozzle extending through said depressed portion, a diaphragm mounted in said body above the cap and having air-inlets, a downwardly tapering tube mounted in said diaphragm and having its lower end extending into the depression, and an electric heater-coil extending around said tube.
  2. In a carburetor comprising a float-chamber and a carbureting chamber, a cap separating said chambers and having a central depression, a fuel nozzle extending through the central part of said diaphragm, means to cause liquid fuel to flow into said depression, a tube in said carbureting chamber and extending downward into said depression, and an electric heater-coil mounted on said tube.
  3. In a carburetor comprising a float-chamber and a carbureting chamber, a cap mounted to separate said chambers and having a central depression, a fuel nozzle extending from the float-chamber into said depression, a downwardly tapering tube mounted in said carbureting chamber and extending into said depression, and an electric heater-coil surrounding the tube above said head, contact posts mounted in the wall of the carbureting chamber and insulated therefrom, and contact plates engaging said posts and connecting to the ends of said coil.
  4. In a carburetor, the combination of a float-chamber, a carbureting chamber, a cap between the two and having a central depression, a fuel nozzle extending from the float-chamber into said depression, a downwardly concave head mounted above said cap and having a down-turned, perforated edge resting thereon, a tube mounted in said head centrally of the same and of said nozzle and the depression in the cap and extending down to the same, an electric heater-coil surrounding the tube above said head, contact posts mounted in the wall of the carbureting chamber and insulated therefrom, and contact plates engaging said posts and connecting to the ends of said coil.
  5. In a carburetor, the combination of a body, a fuel receptacle, a cap forming a top for the fuel receptacle and having a central depression and a fuel passage through said central depression, a diaphragm mounted in said body above the cap and having air inlets, a downwardly extending tube supported by said diaphragm and having its lower end extending into said depression, and a heating element mounted adjacent said tube to heat the same and thereby the fuel in said depression.
  6. In a carburetor, the combination of a body, having a tube forming the lower end of the same, a plate having a centrally depressed portion mounted below said tube, a fuel chamber mounted adjacent the body, a fuel pipe connecting to the fuel chamber and to said plate to conduct fuel to said depressed portion, and a heating element mounted adjacent the tube to heat the lower end of the same and thereby the fuel in the depression in said plate.
  7. In a carburetor comprising a float-chamber and a carbureting chamber, a diaphragm separating said chambers and having a central depression, a fuel-nozzle extending through the central part of said diaphragm, a tube in said carbureting chamber extending downward into said depression, and means to heat said tube.
  8. In a carburetor comprising a float-chamber and a carbureting chamber, a plate mounted to separate said chambers and having a central depression, a fuel-nozzle extending from the float-chamber into said depression, a downwardly tapering tube mounted in said carbureting chamber and extending into said depression, and means to heat said tube.
  9. In a carburetor, a cap with a central depression, with a fuel nozzle projecting

- centrally thereinto, in combination with a centrally apertured dished diaphragm having a perforated circumferential flange resting on said cap, to provide an annular air inlet chamber, a conical carbureting tube extending through the aperture of the diaphragm into the said depression and around the fuel nozzle, and a heater mounted on said diaphragm about the carbureting tube.
- 10 10. In a carbureter, the combination with a case of a diaphragm extending across said case and apertured, a peripheral air inlet at one side thereof, a conical mixing tube engaging a center aperture in said diaphragm, a fuel nozzle directed into said mixing tube, and an electric heater mounted on said diaphragm surrounding said tube.
- 15 11. In a carbureter, the combination of a casing, a diaphragm extending thereacross, centrally apertured and provided with a depending cone, a fuel nozzle directed into said cone, a cup secured to said fuel nozzle and surrounding said cone, and an electric heater mounted on said diaphragm.
- 20 12. In a carbureter, the combination with a casing of an apertured diaphragm extend-
- ing thereacross, an electric heater mounted upon said diaphragm and extending around the aperture therein, and terminals for said heater extending outward through said casing and insulated therefrom.
13. In a carbureter, the combination with an apertured diaphragm, having a peripherally-apertured flange and a central cone, of an electric heater mounted upon said diaphragm between said flange and said cone.
14. In a carbureter, the combination with a casing of a diaphragm removably secured in said casing and having a central cone, an electric heater mounted upon said diaphragm, surrounding said cone, terminals for said heater projecting outward through said case, and insulator bushings for sealing said terminals in said case.
15. In testimony whereof I have signed this specification in the presence of two subscribing witnesses.

CHESTER F. JOHNSON.
